his Attorney

Patented May 31, 1927.

1,630,812

UNITED STATES PATENT OFFICE.

OWEN P. SMITH, OF MIAMI, FLORIDA.

TRACTION CAR AND THE LIKE.

Application filed May 24, 1926. Serial No. 111,153.

The present invention is a continuation in part of my application Serial No. 595,045, filed October 17, 1922, now Patent No. 1,591,569.

5 This invention relates to cars for operation upon rail tracks, and especially to the class of cars mounted upon four flanged wheels, or trucks having four flanged wheels each, to be operated upon tracks having 10 sharp turns which the car is required to make at very high speed.

The object of my present invention is to provide such a car wherein the wheels will automatically follow the curve of the track 15 and thus avoid danger of jumping from the track and injuring the car and causing damage to nearby property.

Another object is to provide such a car, which can be operated from a distance, and 20 without any person aboard the car to steer or guide it on the curves, and which will uniformly and automatically negotiate the curves without jumping the track, no matter how high a speed the car may attain in such 25 curves.

With the above, and other objects in view, which will more particularly appear in the following description, I have shown in the accompanying illustrations one embodiment 30 of my said invention, as applied to electric cars for use on dog racing tracks as patented by me.

In the accompanying drawings, in which like numerals of reference refer to similar 35 parts throughout the various views,

Figure 1 is a top plan view of an electric car showing my construction.

Figure 2 is a side elevation, showing the forward part of the car, with parts removed 40 to show operating parts.

In the construction generally of cars for operation upon rail tracks, it has been customary to mount the cars upon either four flanged wheels, in the case of small cars, or 45 in case of larger cars, upon two trucks of four wheels each. Generally the said wheels are fixedly attached to an axle, and said axle is mounted to rotate in bearings rigidly attached to the frame. This construction 50 holds the forward and rear wheels rigidly in line, whether traveling on a straight track, or around curves, and as a consequence, whenever the car turns a curve, the wheels on one side must slide against the outer rail to 55 adapt the direction to the direction of the curve. While such cars operate quite satis-

factorily on straight tracks, and around large curves at slow speed, yet whenever attempt is made to operate them around a sharp turn at a high speed, they are very likely to jump 60 the track, and even if they do not jump the track, the wear on the flanges of the wheels, and on the outer rail becomes excessive.

The cars which I have illustrated herein, are adapted for use in my dog racing amusement, as patented in former patents to me, and are adapted to operate at high speed 65 around a small track, with sharp turns, and to be operated from the control tower at some distance from the track, and in practice 70 I have found them very safe and efficient.

In the construction of the car illustrated in the accompanying drawings, I have preferably constructed a rectangular frame of angle irons as 1 and 2 for the sides, and 3 75 and 4 for the ends, these parts being securely attached together at the corners by rivets, or welding, as preferred. To support the working parts of said car, and strengthen 80 said frame, I have provided cross members, as 6, 7 and 8, all of which are attached to the side pieces as shown. Near the rear of the frame, as at 9 and 10, I have provided suitable bearings for the axle 11, which is rotatably mounted in said bearings. At the 85 ends of this axle 11 I have fixedly attached the two flanged wheels 12 and 13.

Near the forward part of my frame, I have provided the pivotally mounted cross bar 5, which is mounted at its mid-center upon a 90 bolt, pin or king-bolt 18 passing through the mid-center of said cross-bar, and through an opening provided in the cross piece 6 of the frame. At the extremities of the cross-bar 5 I have provided suitable guides, as 14, 15, 95 16, 17 which are attached to the upper side of said cross bar and then extend upward, and again horizontally to engage the upper edge of the angle irons 1 and 2 forming the side frame of the car, the object of said guides, being to retain the cross-bar 5 in substantially horizontal position while in operation.

An axle 22 is rotatably mounted in two 105 bearings 20 and 21 fixedly attached to said cross-bar 5, and on the extremities of said axle are fixedly mounted the two traction flanged wheels 23 and 24. At 27 and 28 I have shown two tension springs which are located one upon either side of the center or king-bolt attaching the cross-bar to the frame, the other end of each spring being 110

suitably attached to the cross-piece 7 at suitable points for the purpose. I have preferably attached said springs to the cross-bar 5 by means of screw-eyes 32, 32, with nuts 6 upon the opposite side of said cross-bar, thus affording means of increasing or reducing the tension of one or both of said springs, when desired. At 29 I have mounted a suitable electric motor upon said frame, for operation of said car through current supplied thereto by a third rail 33, or other suitable means. A gear wheel 30 upon the shaft of said motor is in mesh with an idle gear wheel 31^a mounted upon the frame, which 10 in turn is in mesh with the gear 31 mounted upon the rear axle 11, and in consequence, whenever the electric motor is rotated in operation the gearing rotates the rear axle, and the rear wheels propel the car along the 15 track 34 and in the usual way.

In the foregoing construction, as will be seen, I have provided front wheels which are mounted to turn sideways, when negotiating a curve, the same as the front wheels 25 of a buggy or automobile are turned in negotiating a curve. By this construction, the wheels can readily adapt themselves to the direction of the curve, and follow the rails around the curve without the usual risk of 30 jumping the track, as when the front and rear wheels are held rigidly in alignment. As my cars are too small to carry an operator to turn the front wheels when approaching the curves, I have provided the 35 means shown consisting of the swiveled front axle, and the tension springs connected from said swiveled axle to the frame. The springs are preferably adjusted by means of the screw-eyes and nuts to such 40 tension as shall be best suited to the purpose for which the car is employed. In straight tracks, or those having slight curves, the tension of the two springs should be slight and equal. On tracks where the car is continually 45 describing a small circle at high speed, as in the dog racing track, the tension of the spring on the outer side should be much less than the one on the inner side, thereby permitting the wheels to turn in the direction 50 of the curve at very slight pressure upon the flange of the outer wheel. While I have shown tension springs in use, yet it is apparent that any equivalent means may be employed to accomplish this result, without departing from the spirit of the invention. 55 While I have shown the front wheel only as swiveled, it is apparent that the rear wheels may also be swiveled, or the rear wheels only swiveled, or that the wheels on one side may be mounted to turn on a pivot, and the wheels on the other side mounted

rigidly. I usually employ weights, of suitable size as 35, 35 mounted upon the forward part of the car to assist in holding the car upon the track.

65

Having thus described my invention, what I claim and desire to secure by Letters Patent, is the following:

1. In a traction car of the class described, the combination with a frame, of a motive power mounted upon said frame, traction wheels mounted upon an axle rotating in bearings rigidly attached to said frame, wheels mounted upon a second axle rotating in bearings mounted upon a support adapted to rotate pivotally about its mid-center, guides on said support and engaging the frame to hold said support in horizontal position and springs connected between said support and the frame adapted to hold said wheels normally in alignment with the aforementioned wheels.

70

2. In a device of the class described, the combination with a motor driven car, of an axle rotatably mounted in bearings rigidly attached to said car, wheels fixedly mounted upon said axle, a second axle rotatably mounted in bearings attached to a cross-bar pivoted at its mid-center to the frame and adapted to turn to right or left, bolts extending through said cross bar and being provided with adjusting means and springs connected from said bolts to the frame on either side of its center adapted to hold said cross bar normally at right angles to the direction of travel of the car.

85

3. In a device of the character described, a frame comprising side and end members, an axle journalled in bearings carried by the frame and having wheels thereon, cross members extending transversely of the frame to form supports, a cross bar pivotally supported by one of the cross members for swinging movement in a horizontal plane, an axle carrying wheels journalled in supports on said pivotal cross bar, guides on said cross bar and extending upwardly and outward to engage the side frame, thereby holding the cross bar in horizontal position, bolts passing transversely through the cross bar on both sides of the pivotal connection between the cross bar and cross member and springs connecting the said bolts with a second cross member to hold said cross bar and the axle carried thereby normally at right angles to the direction of travel of the car, and means for propelling the car carried by the said last mentioned cross member.

90

In testimony whereof, I have duly signed 100 the foregoing specification.

OWEN P. SMITH.
